PLOWSHARE

John A. Romine and John M. Romine,
Etna Green, Ind.

Application February 19, 1935, Serial No. 7,285

2 Claims. (Cl. 97—125)

This invention relates to a plow share, the general object of the invention being to make the share of two pieces, one piece forming the share and the other the point, so that the point can be readily replaced by a new one when the old one becomes worn, thus doing away with the necessity of replacing the share each time a point is renewed, with means for forming a smooth junction of the point with the share, and the parts being so arranged that the point takes the greatest part of the wear, thus saving the share.

This invention also consists in certain other features of construction and in the combination and arrangement of several parts, to be herein-after fully described, illustrated in the accompanying drawing and specifically pointed out in the appended claims.

In describing the invention in detail, reference will be had to the accompanying drawing wherein like characters denote like or corresponding parts throughout the several views, and in which:

Fig. 1 is an elevation of the improved point and share.

Fig. 2 is a fragmentary view looking toward the inner face of the front part of the share.

Fig. 3 is a view looking towards the front end of the share.

Fig. 4 is a bottom plan view of the point.

Fig. 5 is a section on line 5—5 of Fig. 1.

In this drawing, the letter A indicates the share and the letter B the point. The point is provided with a socket 1 in its rear part which fits over the frog of the plow and said point is jammed against the landside. The rear edge of the cutting side of the point is beveled as shown at 2 and a notch 3 is formed in the lower portion of the rear part of the point. The front end of the share A is also beveled as shown at 4 and this bevel overlaps the bevel 2 of the point, as shown in Fig. 5 and the lower part of the front edge of the share is formed with a projection 5 which enters the notch 3, this projection 5 being formed by terminating the bevel 4 an appreciable distance from the lower edge of the share as more particularly shown in Fig. 2. The inner face of the share is formed with the rib 6. The parts are connected to the plow by bolts which pass through the holes 7. A tongue 8 is also formed on the rear edge of the point and engages a notch 9 in the front edge of the share and a lug 10 is formed on the rear end of the point on the in-

ner face thereof and projects rearwardly therefrom and engages a portion of the inner face of the front edge of the share. The member 8 fitting in the notch 9 will protect the point when the point hits a rock or the like and the lug 10 acts to make the connection between the point and share a firm one.

With this invention, the old point can be readily removed when worn and a new one substituted therefor, it not being necessary to replace the share which wears very slowly and as will be seen the parts are so arranged that the point takes the greatest part of the wear thus saving the share.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:

1. In a plow, a share, a point, the adjacent edges of the point and share being beveled with the bevel of the share overlapping that of the point, means for attaching the parts in a detachable manner to the plow, the lower portion of the rear edge of the point having a notch therein and the lower portion of the front edge of the share having a projection thereon fitting into the notch.

2. In a plow, a share, a point, the adjacent edges of the point and share being beveled with the bevel of the share overlapping that of the point, means for attaching the parts in a detachable manner to the plow, the lower portion of the rear edge of the point having a notch therein and the lower portion of the front edge of the share having a projection thereon fitting into the notch, said point having a socket therein receiving part of a plow, the front edge of the share having a notch therein arranged substantially at the center of said edge, a tongue on the rear edge of the point fitting in the notch, and a rearwardly projecting lug on the rear part of the point overlapping the inner face of the front edge of the share.

JOHN A. ROMINE.
